UNITED STATES PATENT OFFICE.

JOHN A. SODERSTROM, OF BUFFALO, NEW YORK.

ATTACHMENT FOR SINK-BOARDS.

1,264,702.

Specification of Letters Patent. Patented Apr. 30, 1918.

Application filed April 30, 1917. Serial No. 165,435.

To all whom it may concern:

Be it known that I, JOHN A. SODERSTROM, a citizen of the United States, residing at Buffalo, in the county of Erie and State of New York, have invented new and useful Improvements in Attachments for Sink-Boards, of which the following is a specification.

This invention relates to a guard for sink boards and the like which prevents dishes from sliding therefrom.

One of its objects is to provide an attachment of this character which is simple in construction and producible at low cost.

15 A further object is the production of a guard which can be readily applied to sinks now in general use and which can be easily removed therefrom for the purpose of cleaning the sink board.

20 Another object is to provide the guard with means for dividing the sink board into a plurality of compartments in which to arrange dishes, silverware, glasses, etc., after being washed.

25 In the accompanying drawings:

Figure 1 is a perspective view of a sink and board to which my improved guard is attached. Fig. 2 is a fragmentary vertical section, on an enlarged scale, on line 2—2, 30 Fig. 1. Fig. 3 is a fragmentary transverse section, on an enlarged scale, on line 3—3, Fig. 1. Fig. 4 is a perspective view of a modified form of my improvement. Fig. 5 is an enlarged sectional view showing the 35 means of attaching it to the sink board.

Similar characters of reference indicate corresponding parts throughout the several views.

Referring to Figs. 1-3, 1 indicates the sink 40 and 2 the sink board to which my improved guard is applied. Both the sink and sink board may be made of any appropriate material, such for example, as enameled iron.

The guard consists of a U-shaped bar 3 45 constructed of a single strip of material having a transverse portion 4 and longitudinal side arms 5, 5, which are adapted to extend around the inner transverse edge and the outer and inner longitudinal edges of 50 the sink board 2 and above the surface thereof a suitable distance to prevent any articles resting thereon from sliding off onto the floor. The inner transverse portion 4 of the guard is preferably hinged to a pair 55 of removable attaching lugs or clips 6 which

embrace the downwardly extending flange 7 of the sink board. These attaching lugs are constructed of a flexible material so that the same can be sprung onto and off from the board. To the upper portion of each lug 6 is 60 fastened one leaf of a suitable hinge 8, while the other leaf is fastened to the inner face of the transverse portion 4 of the guard. The outer longitudinal arm 5 of the latter is provided, preferably on its extreme end, with 65 a locking or retaining clip 9 which may be fastened to the same by a rivet 10 or other suitable means and which serves to reliably hold the guard in place when in use. As shown in Figs. 1 and 3, this retaining clip 70 is adapted to embrace the adjacent edge of the sink board and its inwardly-extending lower end 11 is arranged to snap into a notch or recess 12 in the flange 7 of the sink board. This clip and guard possess the necessary 75 resilience to permit the same to be moved into and out of engagement with the outer longitudinal edge of the sink board. By hinging the guard at its inner transverse edge and providing a locking device of the 80 character described, the same may be easily and readily swung upwardly, as shown by dotted lines in Fig. 3, to a position which will permit of thoroughly cleaning the sink board.

85 For the purpose of dividing the sink board into a series of compartments in which to conveniently arrange dishes, glasses, silverware, etc., after being washed, a plurality of partitions 13 are provided which are arranged transversely of the guard and sink. These partitions are provided at their ends with projections 14 which are adapted to engage notches 15 arranged at suitable intervals in the top edges of the longitudinal side 90 arms 5, 5, of the guard. The top edges of the partitions are preferably flush with the top edges of the guard, while their bottom edges terminate short of the upper surface of the sink to permit water to drain therefrom.

100 In the modification shown in Figs. 4 and 5, the sink guard is constructed of an L-shaped bar 16 which extends around the lower or inner transverse edge and the outer 105 longitudinal edge of the sink board 2^a, and above the surface thereof. The transverse portion of the guard is hinged at 17 to the adjacent edge of this board, which in this instance, is constructed of wood. The side 110

member of the guard is provided with a retaining clip 18 adapted to snap over the adjacent edge of the board for holding it in place. As in the previous construction, the guard is resilient enough to permit this clip to snap into and out of engagement with the edge of the sink board.

It will be noted from the foregoing, that this improved sink guard has few parts, it can be easily attached to any sink now in general use, and can be manufactured at a comparatively low cost.

I claim as my invention:

As an article of manufacture, a guard-attachment for sink-boards comprising a 15 transverse bar adapted to extend along the inner edge of the sink-board and a resilient longitudinal bar adapted to extend along a lateral edge of the board, and means for pivotally mounting said transverse bar on the sink-board to swing said bars clear thereof, said resilient bar having a retaining clip 20 adapted to engage the side of the board.

JOHN A. SODERSTROM.
